FLUORESCENT FIXTURE

Thomas B. Totten, Agincourt, Ontario, Canada, assignor to C&M Products Limited, a company of Canada
Filed Nov. 8, 1961, Ser. No. 151,103
21 Claims. (Cl. 240—51.11)

The present invention relates to a socket plate and end plate structure for fluorescent lighting fixtures.

In present practice socket plates and end plates for fluorescent lighting fixtures are separately formed and finished for mounting on the fluorescent fixtures. In normal practice, it is necessary to form the channel of the lighting fixture, form the socket plate, form the plurality of end plates, paint each of the portions separately, and subsequently assemble the completed fixture.

The present invention overcomes the disadvantages of known fixture constructions by providing a one piece combined socket plate and end plate structure, which may be formed to its finished shape, assembled to the fixture and the whole fixture painted in one operation. It will be readily appreciated that this procedure considerably simplifies the manufacture of a fluorescent lighting fixture. Further the assembly of the fixture is greatly simplified since the socket plate and end plate are formed from one piece of material and are not severed during manufacture. Further in accordance with the invention, portions of the socket plate and end plate assembly may be severed and used for connecting between adjacent channel segments where fluorescent lighting fixtures are mounted in end to end relation, such as is common practice where large areas are to be lit using such fixtures.

Further it will be appreciated that using the socket plate and end plate of the present invention, it is possible to mount the sockets and wire them to the associated electrical equipment in the fixture and then rotate the socket plates so that the sockets lie below the upper edge of the channel of the fixture. Thus the fixture may be very conveniently packaged and quickly assembled for use at its ultimate destination.

The present invention includes the blank from which the socket plate and end plate assembly is formed. In accordance with the present invention a one piece blank for forming a socket plate and end plate structure for a fluorescent lighting fixture comprises a pair of first panels having therebetween a space for receiving a second panel, a third panel joined to said pair of first panels by a first pair of aligned fold lines, a second fold line parallel to said first pair of fold lines and joining said second and third panels, a third pair of parallel fold lines joining each first panel to a fourth panel, said third pair of fold lines extending normal to and intersecting said first pair of fold lines, a fourth pair of aligned fold lines extending parallel to said first pair of fold lines and joining a fifth panel to the said pair of first panels, said second panel on folding along said second fold line being adapted to form a socket mounting plate, said third panel on folding along said first pair of fold lines being adapted to form a front plate and said pair of first panels forming a pair of top plates, said fourth panels on folding along said third fold lines forming a pair of side flanges, said fifth panel on folding along said fourth pair of fold lines forming an end plate.

A socket plate and end plate assembly for a fluorescent lighting fixture constructed in accordance with the present invention comprises a pair of top plates having a space therebetween adapted to receive a fluorescent lighting socket, a front plate connected with and extending at right angles to said top plates, a socket plate connecting said front plate and aligned in a plane parallel to the plane of said top plates, said socket plate being positioned to receive and support a socket positioned in the space

2

between said top plates, a pair of side flanges extending at right angles and in the same direction as said front plate and connected to said top plates, said side flanges being normal to the front plate, and an end plate connected to said top plates and extending parallel to and in the same direction as said front plate.

Such a socket plate and end plate assembly in accordance with the invention may also be formed from a one piece blank having a first panel having an opening therein adapted to receive a fluorescent lighting socket and joined to a pair of second panels by spaced parallel fold lines, a third panel connected to said first panel by a weakened portion, a fourth panel connected to said third panel by a weakened portion parallel to said first weakened portion, said fourth panel being joined to a pair of fifth panels by parallel fold lines parallel with said above mentioned parallel lines, a sixth panel joined to said fourth panel by a fold line parallel to said weakened portions, said second fifth and sixth panels being adapted to be folded in the same direction and at right angles to the first and fourth panels respectively to form a socket plate and end plate joined by said third panel, said third panel being adapted to be severed from said first panel and said fourth panel at said weakened portion, said end plate being adapted to nest within said socket plate for connection thereto.

In drawings which illustrate embodiments of the invention:

FIGURE 1 is a plan view of the blank for forming a combined socket plate and end plate assembly for holding two fluorescent light sockets,

FIGURE 2 is a plan view of the blank shown in FIGURE 1 folded to form a socket plate and end plate assembly,

FIGURE 3 is a front elevation of the assembly shown in FIGURE 2,

FIGURE 4 is a side elevation of the assembly shown in FIGURE 2,

FIGURE 5 is a perspective view showing the joining of a pair of fluorescent lighting fixture channels using sockets and end plate assemblies in accordance with the present invention,

FIGURE 6 shows a socket plate and end plate assembly constructed in accordance with the present invention mounted in the channel of a fluorescent lighting fixture,

FIGURE 7 is a plan view of a blank for forming a socket plate and end plate assembly,

FIGURE 8 is a plan view of the blank of FIGURE 7 folded to form a socket plate and end plate assembly,

FIGURE 9 is a side elevation of the assembly shown in FIGURE 8,

FIGURE 10 is a front elevation of the assembly shown in FIGURE 8,

FIGURE 11 is a perspective view showing the use of the socket plate and end plate in accordance with the present invention where a pair of like channels are to be joined by the end plate structure, and,

FIGURE 12 is a perspective view showing the use of a socket plate and end plate assembly for forming a closed end on a fixture.

As shown in FIGURE 1, a blank for forming a combined socket plate and end plate for mounting a pair of fluorescent lighting sockets in the channel of a fluorescent lighting fixture comprises three top plates 20, 21 and 22. These three top plates are joined to a front plate 23 by means of a fold line 24. A pair of socket plates 25 and 26 are similarly joined to the front plate 23 by a fold line 27. A pair of side flanges 28 and 29 are joined to the top plates 20 and 22 respectively by fold lines 30 and 31 respectively. An end plate 32 is joined to the top plates 20, 21 and 22 by a fold line 33. An end plate extension 34 is connected to the end plate by means of a

weakened line 35, so that the end plate extension 34 may be severed from the end plate 32 along the weakened line 35.

The side flanges 28 and 29 are each provided with outwardly extruded holes 36 and 37. Similarly each of the side flanges 28 and 29 are provided with slots 38 and 39.

The socket plates 25 and 26 are provided with mounting holes 40 for mounting sockets thereon. The end plate 32 is provided with a pair of locking tabs 41 and 42 against which the free ends 43 and 44 of the socket plates 25 and 26 abut when the blank is folded to its finished form. A hole 45 is provided in the top plate 21 to which a closure panel of the fluorescent lighting fixture may be fastened when the fixture has been mounted in its final position. A knock out 46 is provided in the end plate 32 in the usual manner to provide access to the interior of the fixture for connecting electrical connections to the sockets of the ballast.

The end plate extension 34 is provided with a pair of holes 47 and 48 of diameter adapted to receive the extruded edges of holes 36 and 37 in the side flanges 28 and 29. Similarly a pair of smaller diameter holes 49 and 50 are provided adjacent the centre of the end plate extension 34 through which fastening screws may be threaded.

FIGURE 2 shows the socket plate and end plate as formed from the blank of FIGURE 1. It will be seen that the front plate 23, the side flanges 28 and 29 and the end plate 32 have been folded normal to the top plates 20, 21 and 22. The socket plates 25 and 26 have also been folded normal to the front plates 23 and thus lie below and parallel to the top plates 20, 21 and 22. Thus spaces are provided between the top plates 20, 21 and 22 in which the sockets of the fluorescent lighting fixture may be mounted. As may be seen in FIGURE 2 the tabs 41 and 42 serve to support the free ends 43 and 44 of the socket plates 25 and 26. It may also be seen that the hole 45 is suitably positioned for having a retaining screw passed therethrough to retain the cover on the fixture.

The extruded holes 36 and 37 may be seen to project from the side plates 28 and 29 and thus may be inserted in holes of suitable size formed in the sides of the fixture, for retaining the socket plate and end plate assembly in position. It will also be appreciated that the extruded holes 36 and 37 will serve as a pivot around which the socket plate and end plate assembly may be pivoted in the fixture.

FIGURE 3 is a front view of the socket plate and end plate of FIGURE 2 and clearly shows that the socket mounting plates 25 and 26 are spaced below and parallel to the top plates 20, 21 and 22.

Similarly FIGURE 4 clearly shows that the combined socket plate and end plate assembly is closed in at the top and sides providing a self-contained and complete unit.

FIGURE 5 shows a pair of like fluorescent fixture channels 51 and 52 in which a pair of socket plate and end plate assemblies constructed in accordance with the present invention are used and wherein a pair of end plate extensions are used to connect the adjacent channel segments together. It will be appreciated that one of the two socket plate and end plate assemblies is not visible in this perspective view, its presence being indicated by the pair of end plate extensions 53 and 54 shown in the figure. As may be seen a socket plate and end plate assembly 55 is mounted in the channel 52, the extruded hole in each side of the assembly 55 fitting within holes formed in the sides of the channel 52. The end plate extensions 53 and 54 are similarly positioned so that the extruded holes are within the hole in the end of the end plate extension. As may be seen the two fixture channels are assembled together by inserting screws 56 into the central holes in the end plate extension 54 and similarly screws are inserted in the end plate extension 53. The holes in the outer ends of each of the end plate extensions are placed over the extruded hole in the opposite assembly. Subse-

quently, screws are passed through holes provided in the walls of the channels and threaded into the extruded holes in the assemblies. These screws may conveniently be of the self-tapping or sheet metal type.

FIGURE 6 shows a pair of fluorescent lighting sockets 60 and 61 mounted in a socket plate and end plate assembly 62 which is in turn mounted in a channel 63 of a fluorescent lighting fixture. The end plate 64 is shown with the end plate extension 65 removed and with a hole 66 therein formed by the removal of the knock-out. It will be appreciated that when the knock-out is removed to form the hole 66 that the end plate 65 would not simultaneously be removed.

FIGURE 7 is a plan view of a blank for forming a combined end plate and socket plate assembly for a fluorescent lighting fixture, which consists of a top plate 20', a pair of side flanges 28' and 29', an end plate 32' having a knock-out 46' therein, a pair of side tabs 70 and 71 fixed to the end plate 32' by means of fold lines 72 and 73 and a bottom tab 74 fixed to the end plate 32' by a fold line 75. The end plate 32 is connected to the top plate 20' by means of a top tab 76 which is fastened to the end plate 32' by a weakened portion 77 and to the top plate 20' by a weakened portion 78. As before a pair of extruded holes 36' and 37' are formed in the side flanges 28' and 29' for connecting the top plate and end plate assembly to the fixture. The side flanges 28' and 29' are adapted to be folded normal to the top plate 20' and parallel to each other to form the side portions of the socket plate assembly. Similarly, side tabs 70 and 71 of the bottom tab 74 are adapted to be folded in the same direction as the side flanges 28' and 29' to form an end plate assembly. The combined socket plate and end plate assembly is in this form, fastened to the channel of a fluorescent lighting fixture and the channel together with the assembly is painted as a unit.

The appearance of the assembly prior to being fastened to the channel of the fixtures is shown in FIGURES 8, 9 and 10. FIGURE 8 being a plan view, FIGURE 9 is a side elevation and FIGURE 10 is a front elevation of the assembly after it is folded. It will be noted in FIGURE 9 that each of the side tabs 70 and its counterpart 71 is provided with three holes, which may be used for connecting the end plate portion of the channel of the fixture as is shown in FIGURES 11 and 12.

FIGURE 11 illustrates the method of connecting the end plate assembly to the channel of a fixture when a pair of like channels are to be joined using the end plate. As shown the top tab 76 has been severed from the top plate 20' and the socket plate assembly along the weakened portion 78. The top tab 76 is then folded at right angles to the end plate 32' and is fastened in the end of the channel of each fixture using the screws 80 passing through the holes 81 and 82.

As shown in FIGURE 12 when the channel of the fixture is not to be connected to an adjacent channel the end plate 32' is placed in a vertical position and affixed to the channel by means of the screw 80 passing through either the hole 83 or the hole 81. If no electrical connections are to be made through the knock-out 46' then the top tab 76 is broken from the end plate 32' and the screw 80 is passed through hole 81. If, however, electrical connections are to be made through the knock-out 46' then additional space is required at the end of the fixture and the top tab 76 is folded down to lie between the side tabs of the end plate assembly and is fastened to the channel of the fixture by passing the screw 80 through the hole 83.

Thus a variety of alternate constructions are provided for with a single blank and the manufacture of the fixtures is greatly simplified. As previously mentioned the sockets may be mounted on the socket plate assembly and wired to the ballast and the external connections after which the socket plate assembly may be rotated about the extruded holes so that the sockets lie within the channel of

the fixture. The fixture will thus occupy less space for shipping and there will be less chance of damaging the sockets. When the fixture is to be placed in service the sockets may be rotated to their erect position and screws passed through the socket plate assembly to hold it firmly in place.

The embodiments of the invention in which an exclusive property or privilege is claimed are defined as follows:

1. A combined end and socket plate assembly for a fluorescent lighting fixture having a channel member, said assembly formed from a one piece blank having a first panel portion having an apertured top for said assembly; a pair of second panel portions articulated to opposed ends of said top and extending normal to the plane of said top, thereby to provide a spaced pair of side flanges thereon, each of which when assembled with a lighting fixture channel member bears against an associated leg portion of said channel member in substantially face-to-face contact therewith, each side of said second panels having pivot means for attachment to the associated leg of said channel; and a third panel portion articulated to a side of said top and extending in the same direction as the side flanges, said third panel portion being adapted to provide said end plate of said assembly, said end plate being adapted substantially to enclose the open end of said channel, at least a portion of said third panel being separable from said assembly to provide a connector for a pair of lighting fixtures disposed end-to-end.

2. A member as defined in claim 1 wherein said blank includes a fourth panel portion articulated to said top on the side opposite to said third panel and adapted to be normal to said top to provide a front wall for said assembly and at least one further panel defined by a U-shaped slit having the open ends thereof terminating in said front wall, said further panel extending in a direction toward said third panel defining the end plate of the assembly.

3. A device according to claim 1 wherein said blank is formed of metal.

4. A device according to claim 1 wherein said first panel portion is provided with at least one mounting hole for fastening a fluorescent lighting socket to said panel.

5. A device according to claim 1 and wherein a knock-out portion is provided in said third panel portion.

6. A device according to claim 1 wherein said pair of second panel portions are each provided with a hole, the edge portions of which are extruded in such a manner that when the blank is formed into a socket plate and end plate structure the edges of the hole are extruded outwardly and project into associated apertures in the legs of said channel.

7. A device as defined in claim 2 wherein said further panel abuts against the third panel which forms said end and bears upon a tab struck out from said end.

8. A combined socket plate and end plate assembly for a fluorescent lighting fixture comprising a top plate having at least one aperture therein adapted to receive a fluorescent lighting socket, a front plate connected with and extending at right angles to said top plate, a pair of side flanges extending at right angles and in the same direction as said front plate and connected to said top plate, said side flanges being normal to the front plate, and an end plate connected to said top plate and extending parallel to and in the same direction as said front plate and a socket plate struck out from said end plate to abut said front plate and being disposed to underlie the aperture in said top plate and extending in a plane parallel to the plane of said top plate, said socket plate being positioned to receive and support a fixture socket disposed in said aperture.

9. A combined socket plate and end plate assembly for a fluorescent lighting fixture according to claim 8 wherein the portion of said end plate remote from said top plate is joined to the remainder of said end plate by a weakened portion and is adapted to be severed from said end plate.

10. A combined socket plate and end plate assembly

according to claim 8 wherein said end plate is provided with a knock-out portion.

11. A combined socket plate and end plate assembly according to claim 8 wherein said end plate is provided with a pair of locating tabs adapted to support the free ends of the socket plates.

12. A combined socket plate and end plate assembly according to claim 8 wherein said side flanges are each provided with an outwardly extruded hole and adapted to engage a corresponding hole formed in the side wall of the fixture to which said combined socket plate and end plate assembly is affixed.

13. A combined socket plate and end plate assembly according to claim 8 wherein each side flange is further provided with a slot through which a fastening may be passed to fix the combined socket plate and end plate in the fluorescent lighting fixture.

14. A combined socket plate and end plate assembly according to claim 13 wherein the portion of said end plate remote from said top plates is connected to said end plate by a weakened portion and is adapted to be severed from said end plate, said severed portion being provided with at least four holes, the holes being arranged longitudinally of the severed portion, the outermost holes being adapted to receive the outwardly extruded holes in said side flange, the innermost holes being adapted to receive fastening means extending through said holes and through said slot in said side flange.

15. A combined socket plate and end plate for a fluorescent lighting fixture having a channel member, said assembly being formed from a one piece blank having a first panel including an opening therein adapted to receive a fluorescent lighting socket and a pair of second panels disposed respectively at opposed ends of said first panel and articulated along spaced parallel fold lines, a third panel connected to said first panel by a linear weakened portion and disposed between said pair of second panels, a fourth panel connected to said third panel by a linear weakened portion parallel to said first weakened portion, said fourth panel being side joined to a pair of fifth panels by fold lines parallel with said above mentioned parallel fold lines, a sixth panel joined to said fourth panel by a fold line parallel to said weakened portions, said second, fifth and sixth panels being adapted to be folded in the same direction and at right angles to the first, and fourth panels respectively to form a socket plate and end plate joined by said third panel, said third panel being adapted to be severed from said first panel and said fourth panel at said weakened portion, said end plate being adapted to nest within said socket plate and adapted for connection thereto.

16. A one piece blank according to claim 15 wherein said second panels are provided with an extruded hole on each of said second panels, said extruded holes being adapted on folding of said blank to cooperate with corresponding holes formed in the walls of the fluorescent lighting fixture, to mount said socket plate to said fluorescent lighting fixture.

17. A one piece blank according to claim 15 wherein said fourth panel is provided with a knock-out portion.

18. A one piece blank according to claim 15 wherein said fifth panels are provided with a plurality of openings through which fastening means may be passed for fastening the folded end plate and a lighting fixture.

19. An integral socket plate and end plate assembly for a fluorescent lighting fixture comprising a top plate having an opening therein adapted to receive a fluorescent lighting socket, a pair of side flanges extending normal to said top plate and having therein extruded holes for engagement to corresponding holes formed in the side walls of a lighting fixture, a top tab connected to an end of said top plate by a weakened portion and to an end plate by a further weakened portion, a pair of side tabs extending normal to said end plate in the same direction as the side

flanges extend from said top plate, and a bottom tab extending from an end of and normal to said end plate in the same direction as said side tabs, said end plate being adapted to be severed from said top plate by separating said top tab from said top plate and for subsequent mounting in nesting engagement with said socket assembly.

20. A socket plate and end plate assembly according to claim 19 wherein said end plate is provided with a knock-out.

21. A socket plate and end plate assembly according to claim 19 wherein said side tabs are provided with a plural-

5 ity of openings for fastening said side tabs to said socket plate and to a lighting fixture.
